(57) **CLAIM**

The ornamental design for a syringe tip cap for liquid dispensing machine, as shown and described.

DESCRIPTION

FIG. 1 is a front view of a syringe tip cap for liquid dispensing machine showing my new design;

FIG. 2 is a back view thereof;

FIG. 3 is a right side view thereof;

FIG. 4 is a top plan view thereof;

FIG. 5 is an A-A cross-sectional view thereof;

FIG. 6 is a perspective view thereof; and,

FIG. 7 is a reference view thereof, showing a state of use. In the drawings, the broken lines depict portions of the syringe tip cap for liquid dispensing machine that form no part of the claimed design.
